UNITED STATES PATENT OFFICE

JOHN MARTIN BARR, OF INDIANAPOLIS, INDIANA, ASSIGNOR TO FAIRBANKS-MORSE ELECTRICAL MANUFACTURING COMPANY, OF INDIANAPOLIS, INDIANA, A CORPORATION OF INDIANA.

RESISTANCE-RING OF ROTORS.

1,079,629.

Specification of Letters Patent. Patented Nov. 25, 1913.

Application filed December 6, 1912. Serial No. 735,266.

To all whom it may concern:

Be it known that I, JOHN MARTIN BARR, of the city of Indianapolis, county of Marion, State of Indiana, have invented certain new and useful Improvements in Resistance-Rings of Rotors, of which the following is a full, clear, and exact description, such as will enable those skilled in the art to make and use the same, reference being had to the annexed drawings, which are hereby made a part of my specification.

My invention relates to squirrel-cage rotors which are used in alternating current induction motors, and more particularly to those squirrel-cage rotors whose conductors bars are connected together by means of a resistance ring of high conductivity.

For many years copper resistance rings have been cast upon the copper conductors of squirrel-cage rotors, but this practice has been in many respects unsatisfactory owing to the fact that the union effected between the resistance ring and the conducting bars of the rotors, varies in its mechanical and electrical characteristics. This was due largely to the wide differences in the quality of commercial copper, to the formation of copper oxid about the conducting bars and also to the fact that air-holes, cracks and voids occurred at the point of union between the conducting bars and the resistance rings. It is a peculiarity of induction motors that any impairment in the perfection of the conductivity of the secondary elements has a tendency to aggravate itself with continued operation. No satisfactory means for ascertaining the existence of these latent defects was found. A rotor with cast end rings or resistance rings may appear entirely satisfactory on external examination and may even show satisfactory on test, but after being in service a time it will then demonstrate the existence of the hidden faults. I have in this my invention discovered a facile means for examining said defects, whereby they may be corrected by suitable local treatment thereof, before the rotor having such a defective resistance ring shall have been shipped from the factory. By my invention I likewise increase the ventilating surface of said resistance rings and thereby prevent their overheating.

Though my invention consists largely in the construction and arrangement of parts

hereinafter described and particularly pointed out in the claims, yet I do not limit my invention to the precise form or construction of parts shown or the several parts thereof, inasmuch as various alterations may be made without changing the scope of my invention.

In the drawings Figure 1 shows a rotor having a resistance ring with my inspection grooves therein, Fig. 2 shows a cross section of a resistance ring with a partly fused conductor bar therein and shows the inspection groove extending into said conductor bar. Fig. 3 shows an arrangement wherein the inspection grooves are cut into the inner periphery of the resistance ring, parallel to the conducting rods or bars and extending slightly into the same. Fig. 4 shows a cross section of a resistance ring, in the face of which is cut an inspection groove, and also a groove on the inner periphery thereof.

In the drawings 5 indicates the rotor laminæ, 6 the conducting bars, 7 the ends of the conducting bars embedded in the resistance ring. These ends are notched or grooved in divers ways for the purpose of securing a better fusion with the resistance ring metal. 9 indicates an inspection groove cut in said ring. These grooves may be of any suitable shape but we prefer to use grooves of the shape of the letter V. These inspection grooves may be cut in the inner periphery of the resistance rings as well as on the outer periphery or on the face thereof. A number of these grooves may be cut upon a resistance ring as may be desired.

In Fig. 3 I show an arrangement in which there are as many inspection grooves as there are conducting bars on the rotor. These grooves extend through the inner part of the resistance ring into a portion of the conducting bars which has been fused.

The inspection grooves shown in figures of the drawing show the greatly increased radiating surface obtained by their use. This increase in radiating surface is of great value in preventing the overheating of these rings. The inspection grooves reaching down to the point where the union of rotor bars and the ring take place, allows one to readily discover the blow-holes, cracks or other imperfections in the ring and these may thereupon be treated locally in any suitable manner to eliminate the same.

What I claim as my invention is:

1. In an electric rotor, a conducting bar, a resistance element integrally united with and making electrical connection with an end of said conducting bar; said resistance element having an opening therein to reveal the integral union of said bar and the resistance element.
  2. In an electric rotor, a conductor, a resistance element embracing an end of said conductor and integrally united therewith and having an opening formed through said element to the embraced end of said conductor.
  3. In an alternating current rotor, conducting bars, a resistance ring, having a groove therein, cut to a point where the bars are united with the metal of said ring.
  4. In an alternating current motor, con-
- ducting bars, a resistance ring, having an opening in said ring extending therein and 20 exposing a portion of the said bars in contact with the metal of said ring.
5. An electric rotor comprising two conjointly united elements, one of which is provided with an opening to reveal the homogeneous union of the two elements.
6. In a rotor, of the class specified, a pair of elements jointly united for interelectrical conductivity; there being a notch formed which extends through the material of each 30 element to reveal at least a portion of the joint surfaces of the elements.

JOHN MARTIN BARR.
